UNITED STATES PATENT OFFICE

JOHN M. CLARK, OF DETROIT, MICHIGAN, AND IRA D. FORD, OF ROSELAND, ONTARIO, CANADA, ASSIGNEES TO UNIVERSAL BUTTON FASTENING & BUTTON CO., OF DETROIT, MICHIGAN, A CORPORATION OF MICHIGAN

BUTTON

Application filed September 26, 1927, Serial No. 221,891. Renewed August 16, 1929.

This invention relates to buttons for workmen's clothing and the like, and aims to provide an inexpensive and durable button which may, if desired, be made with low manufacturing and labor costs.

The invention may be readily understood by reference to one illustrative button embodying the invention and illustrated in the accompanying drawing.

10 In said drawing:

Fig. 1 is a sectional elevation of the button fastened to a fabric or the like.

Fig. 2 is a bottom plan view of the button, the attaching fastener prongs being shown in 15 section.

Fig. 3 is a sectional elevation of the button.

The illustrative button comprises in this instance three elements, namely, the button body 10, the decorative and protective shell 11, and a bar 12. The button body 10 is formed to provide the head 13 and shank 14, the end of the latter being recessed as at 15 to receive a pronged attaching fastener.

25 The body is advantageously made of soft steel or other metal in the form of rod or similar stock (which is quite inexpensive, compared with sheet metal stock) and brought into the illustrated shape by one or 30 more die pressing operations upon a blank or slug cut from the rod stock. These die operations advantageously include the formation of the recess 15. The bar 12 may be appropriately secured in place by welding, 35 for example, or by crimping over the marginal flanges 16 as shown at 17, after the bar 12 has been positioned.

40 After formation the button is preferably treated superficially to improve its appearance and to provide a protective coating. For example, the decorative finish or coating on the head of the button may be provided by a shell 11 formed of relatively thin metal which is either itself rust proof, or treated superficially to render it rust proof. Its outer surface may be provided with any desired decorative embossing or trade-mark, depending upon what the purchaser desires. It is 45 secured to the button by crimping its marginal

flange 18 around and underneath the head 13 of the button.

The bar 12 typifies the means for attaching the button. In the present case such attachment is effected by the double prong-fastener 19, the prongs 20 of which straddle the bar 12 and are bent around it by the bottom 21 of the recess 15 which is advantageously curved to form an upsetting die.

55 The illustrative button is not only an inexpensive button since it is made of but two relatively inexpensive elements (not including the decorative or protective finish which in this instance includes the shell 11) but its construction is such as to lend itself well to 60 economical manufacture, requiring little or no handling. For example, the body 10 of the button may be formed in a series of operations which involve no manual handling and, without intervening manual handling, 65 the bar 12 may be formed and attached to the button body in subsequent operations. Then if desired, without handling the button may be given its protective or decorative finish. While the button is advantageously adapted 70 to be formed economically in the aforesaid or similar manner, its manufacture is obviously not limited to fully automatic manufacture or to manufacture according to a 75 definite sequence of operations.

80 Obviously the invention is not limited to the details of the embodiment thereof herein illustrated and described, since these details may be variously modified. Moreover, it is not indispensable that all features of the invention be used conjointly, since certain features may be advantageously used in various different methods, combinations and sub-combinations.

Having described one embodiment of our 90 invention, we claim:

1. A solid metal button for overalls and the like comprising in combination a die formed body having an integral head and solid shank, said head having a superficial 95 covering, the end of said shank having a semi-spherical, open recess formed therein and a transverse wire bar welded in said recess, the inner surface of said recess being curved to provide a die for bending the 100

prongs of a double pronged fastener over said bar.

5 2. A metal button for overalls and the like comprising in combination an integral button head and solid shank formed from a solid blank, said shank having a semi-spherical recess in its extremity and a transverse round wire bar secured therein, the curved surface of said recess serving as a die to bend the prongs of a fastener about said bar, and a shell of relatively thin metal capable of being embossed covering the face of the button head to protect and finish said head.

10 3. A solid metal button for overalls and the like comprising in combination a die formed body having an integral head and solid shank, said head having a protective surfacing, the end of said shank having an open recess formed therein with a concave bottom, and a transverse fastener receiving bar welded across said recess, said concave surface of said recess serving to provide a die for bending the prongs of a double pronged fastener over said bar.

15 25 In testimony whereof, we have signed our names to this specification.

JOHN M. CLARK.
IRA D. FORD.
